UNITED STATES PATENT OFFICE.

DUDLEY MAYO MASON, OF KENT, OHIO, ASSIGNOR TO THE MASON TIRE & RUBBER COMPANY, OF KENT, OHIO, A CORPORATION OF OHIO.

DESIGN FOR A TIRE-TREAD.

51,683.

Specification for Design.

Patented Jan. 8, 1918.

Application filed November 23, 1917. Serial No. 203,638. Term of patent 14 years.

To all whom it may concern:

Be it known that I, DUDLEY M. MASON, a citizen of the United States, residing at Kent, in the county of Portage, State of Ohio, have invented a new, original, and ornamental Design for Tire-Treads, of which the following is a specification, reference being had to the accompanying drawing, forming part thereof.

In the accompanying drawing:

Figure 1 represents a plan view of a sec-

tion of a tire formed with my improved tread; Fig. 2 represents a side elevation of the tire section shown in Fig. 1; and Fig. 3 represents a vertical section taken in the plane indicated by the lines III—III, Fig. 1.

I claim:

The ornamental design for a tire tread, substantially as shown.

Signed by me, this 14th day of November, 1917.

DUDLEY MAYO MASON.
